UNITED STATES PATENT OFFICE.

ALBION P. COLE, OF WALTHAM, ASSIGNOR TO JOHN W. SMITH, OF BOSTON,
MASSACHUSETTS.

EYE-PROTECTOR.

SPECIFICATION forming part of Letters Patent No. 387,709, dated August 14, 1888.

Application filed December 24, 1887. Serial No. 258,876. (No model.)

To all whom it may concern:

Be it known that I, ALBION P. COLE, a citizen of the United States, and a resident of Waltham, in the county of Middlesex and State of 5 Massachusetts, have invented new and useful Improvements in Eye-Protectors, of which the following, taken in connection with the accompanying drawings, is a specification.

This invention relates to improvements in 10 eye-protectors, and it is particularly designed for use by barbers and hair-dressers for the purpose of protecting the eyes of their customers while trimming the beards, it being well known that during such operation small 15 pieces of hair frequently snap from the scissors and are liable to strike the eyes of the party having his beard trimmed. The eye-protector is intended to be laid loosely on the forehead and cheeks of the customer while it is 20 in use, or it may be provided with a suitable fastening device, if so desired, particularly if the protector is to be used for invalids to shade or guard weak, diseased, or injured eyes.

25 The invention is carried out as follows, reference being had to the accompanying drawings, wherein—

Figure 1 represents a perspective view of the eye-protector. Fig. 2 represents a horizontal section on the line A B shown in Fig. 30 1; and Fig. 3 represents a cross-section on the line C D, also shown in Fig. 1.

Similar letters refer to similar parts wherever they occur on the different parts of the 35 drawings.

a is the protector, having on each side of its center a concave or cup-shaped part, a', adapted to rest against the forehead and upper part of the cheeks while being used. 40 a" is a cut-away portion at the lower and middle junction of the cup-shaped or concave parts a' a' to permit the nose of the wearer to project at such place, so as to enable the outer edges of the protector to lie in close contact 45 with the face of the person using it.

To the edges of the cut-away portion a" is secured a nose-protector, b, made of cloth or suitable soft and flexible material, that will easily conform itself to the shape of the wearer's nose, and thus prevent the hair-clippings 50 from reaching the eyes at this point.

The protector is preferably made of paste-board or leather-board and molded to the desired form; but it may be made of thin metal, wood, wire-gauze, or other suitable material 55 or materials without departing from the essence of my invention.

The concave portions a' a' are to be made deep enough to enable the party to open his eyelids and to close them at pleasure without 60 coming in contact with the interior of the protector.

In hair-cutting establishments the person having his beard trimmed or cut generally 65 reclines in a barber's chair, and during such operation if it is desired to protect his eyes from the hair-clippings it is only necessary to place the protector loosely on his face, the upper edge resting on the forehead and the lower edges on the cheeks, while the bridge of the 70 nose is covered by the flexible cloth gore-piece b, as above described.

What I wish to secure by Letters Patent, and claim, is—

The eye-protector a, having concave or cup-shaped portions a' a' on either side of its middle portion, a midway cut-away portion, a", and a flexible gore-piece, b, secured to the 75 edges of the said portion a", substantially as and for the purpose set forth.

In testimony whereof I have signed my name to this specification, in the presence of two subscribing witnesses, on this 16th day of December, A. D. 1887.

ALBION P. COLE.
